UNITED STATES PATENT OFFICE.

EDWARD WILLIAM OUSLEY, OF ST. JAMES, MISSOURI.

GOLD-DUST COLLECTOR.

1,255,040.

Specification of Letters Patent. Patented Jan. 29, 1918.

Application filed April 2, 1917. Serial No. 159,302.

To all whom it may concern:

Be it known that I, EDWARD W. OUSLEY, a citizen of the United States, residing at St. James, in the county of Phelps and 5 State of Missouri, have invented certain new and useful Improvements in Gold-Dust Collectors; and I do declare the following to be a full, clear, and exact description of the invention, such as will enable others skilled 10 in the art to which it appertains to make and use the same.

This invention relates to dust catchers and more particularly to that class of dust catchers which are used in dental work or whenever 15 abrading operations are carried on upon valuable material, the dust of which it is desired to collect and save.

The principal object of my invention is to provide an improved dust collector of this 20 character which may be readily attached to the person of an operator or secured to a stationary support as desired and is provided with a receptacle at its lower end for collecting the dust therein which may be 25 readily detached from the main body of the collector whenever desired.

Another object of my invention is to provide a device of this character having a foraminous guard whereby, should the plate 30 or material being worked upon be accidentally dropped within the body of the collector, it will be prevented from becoming lodged in the dust collecting receptacle carried on the lower end of the collector.

35 With these and other general objects in view, which will appear from the description, my invention resides in the novel combination, construction and arrangement of parts to be hereinafter more fully described and claimed and taken in connection with the accompanying drawing which forms 40 part of this application and in which:—

Figure 1 is a front elevation illustrating the manner of application of my invention;

45 Fig. 2 is a side elevation of the same;

Fig. 3 is a vertical central sectional view of my collector;

Fig. 4 is a rear elevation thereof;

Fig. 5 is a perspective view of a support 50 for the collector;

Fig. 6 is a side elevation showing my collector as attached to the wall or stationary support.

Briefly described, my invention comprises 55 substantially a funnel-shaped body provided with a detachably secured dust collecting re-

ceptacle on its lower end and having extended across its top an arched transparent guard member. The sides of the body below the arched guard member are deeply recessed in order to provide apertures therethrough for the insertion of the hands of an operator and the body portion of the collector is provided with a hingedly secured hook, whereby it may be suspended from the shoulders of an operator. An additional attaching member is provided at the back of the receptacle whereby the same may be secured upon a wall or any suitable stationary support as desired. Means are also provided at the lower end of the body to prevent the dropping into the dust collecting receptacle of any plates or other materials being worked upon, should the same become accidentally disengaged while being held within the body of the collector.

Referring more particularly to the drawings and describing my invention in detail, my improved collector comprises a substantially funnel-shaped body 1 having a flat 80 rear side 2 and a substantially similar front side 3. The bottom of the body 1 terminates in a spout 4 provided with an annular shoulder 5 depending therefrom and internally threaded to receive therein the externally 85 threaded head of a dust collecting receptacle 6 which may be composed of any suitable material which in this embodiment comprises glass. Adapted to be disposed in the shoulder portion 5 and resting on the head 90 of the receptacle 6 is a frame 7 carrying a foraminous guard member 8 which extends across the mouth of the dust collecting receptacle and forms an effectual guard, whereby to permit the passage therethrough of the 95 small particles of dust to be collected, and which will prevent the dropping of large pieces of material therethrough, should they become disengaged from the tools used by the operator.

The front wall or side of the body of my improved collector is provided with an upwardly extending lip 9 and the rear wall 2 is provided with a similar upwardly extending portion 10 having its upper edge disposed considerably above the upper edge of the projecting lip 9 on the front wall 3 of the collector. The upper edges of the lip 9 and upwardly extending portion 10 are formed of equal length and are connected at 110 their side edges by means of a pair of arched metal strips 11 suitably secured at

their ends to the upper edges of the portion 10 and lip 9 and between which is extended and secured therein a sheet of transparent material such as mica, celluloid or any suitable substance to form the guard member for the top of the body of the collector, and also to provide a means whereby an operator may be enabled to examine the work held within the body of the collector.

10 Owing to the disposition of the upper edges of the upwardly extending portion 10 of the rear wall 2 and the lip 9 on the front wall 3, the arched strips or frame supporting members 11 will be extended downwardly at the front wall of the collector and having a transparent guard member secured therebetween will provide not only a transparent top for the receptacle but a transparent portion disposed at the front of the receptacle as well, thereby insuring a more efficient lighting of the interior of the collector.

Spaced below the arched supporting strips 11, the side edges 12 of the body of the receptacle extending between the upwardly projecting portion and the lip are deeply recessed to provide sufficiently large apertures at the sides of the collector, whereby to permit the insertion of an operator's hands to manipulate tools within the interior of the collector. Between the edges of the aperture thus formed and the front and rear walls of the body of the collector is left a suitable margin so that the hands of an operator when engaged in the apertures will effectually close the same.

As a means of providing a support for the collector, I provide a rod 13 hingedly connected to the back of the collector by means of a flange 14 formed on the upper edge of the projecting portion 10 and surrounding the rod 13 to retain the same thereon. At its opposite ends the rod is provided with upwardly extending portions 15 having hooks 16 formed on their upper ends and adapted to be engaged over the shoulders of an operator when it is desired to use the collector. Owing to the flat rear side of the body of the collector, when the same is engaged with the hooks over the shoulders of an operator, turning or twisting of the body of the collector will be effectually prevented. An apertured flange 17 is formed on the upwardly extending portion 10 of the rear wall so that the body of the collector may be supported on the wall or on a stationary support as desired and owing to the hinged connection, the rod 14 and the hook members thereon, the same may be swung down adjacent the lower portion of the body of the receptacle and disposed so as to not interfere with the placing of the body of the collector upon a suitable support.

While I have shown and described certain specific details and materials used in the construction of my invention, I desire it to

be understood that I do not limit myself specifically to these details as shown and described as it is obvious that the body of the collector may be made of any suitable material instead of aluminum which I preferably employ and that minor changes in the details of its construction may be made without in any way departing from the spirit of my invention and defined between the scope of the following claims.

I claim:

1. A dust collector as described comprising a substantially funnel-shaped body, a dust receptacle to be secured on its lower end, a foraminous guard to be disposed on the lower end of said body, a transparent guard at the top thereof, the sides of said body being apertured to permit of the insertion of the hands of an operator therethrough.

2. A dust collector as described comprising a substantially funnel-shaped body, a dust receptacle on its bottom, a transparent guard member disposed over the top of said collector, the said collector being provided with apertures in its sides to permit of the insertion of the hands of an operator below said transparent guard member, a hook member hingedly secured on said body to engage over the shoulders of an operator, and means on said body whereby to secure the same on a support as desired.

3. A dust collector as described comprising a substantially funnel-shaped body, a sheet of transparent material extended across the top of said body and secured thereto, the side edges of said sheet and body being spaced apart to form oppositely disposed apertures in the sides of the collector, a hook member to engage the shoulders of an operator and foldable on said body, and an attaching lug on said body to secure the same to a stationary support when said hook is folded.

4. A dust collector as described comprising a substantially funnel-shaped body, a frame extending across the upper end of said body, a sheet of transparent material in said frame, the side edges of said frame being substantially arched above the top of said body to provide open portions therebetween at opposite sides of the collector.

5. A dust collector as described comprising a substantially funnel-shaped body, upwardly extending portions at opposite sides of the body, one of said portions extending above the other, a frame extending between the tops of said portions and spaced above the top of the body, and a sheet of transparent material secured in said frame.

6. A dust collector as described comprising substantially a funnel-shaped body having a side portion projecting above the top of the body, an upwardly projecting lip at the opposite side of the body, the top edge

of said upwardly projecting portion being disposed above the top of said lip, a pair of arched supporting members extending between the tops of said upwardly projecting portions, a sheet of transparent material secured thereto, the sides of said body below the arched supporting members being deeply recessed to provide apertures therein, a receptacle for dust detachably secured on the lower end of said body, and means on said

body to attach the collector to an operator or to a support as desired.

In testimony whereof I have hereunto set my hand in the presence of two subscribing witnesses.

EDWARD WILLIAM OUSLEY.
